Patented Oct. 4, 1960

188,955

COMBINED HARVESTER AND THRESHER

Ernest M. Van Buskirk, East Moline, Ill., assignor to
International Harvester Company, Chicago, Ill., a cor-
poration of New Jersey

Filed Apr. 28, 1958, Ser. No. 50,632

Term of patent 14 years

(Cl. D40—1)

FIG. I

Des. 188,955

PAGE 2

FIG.2

Des. 188,955

PAGE 3

FIG. 3

FIG. 4

Fig. 1 is a front perspective view taken from the right side of a combined harvester and thresher showing my new design;

Fig. 2 is a front perspective view taken from the left side thereof;

Fig. 3 is a right side perspective view taken from the top thereof; and

Fig. 4 is a rear elevational view thereof.

I claim:

The ornamental design for a combined harvester and thresher, substantially as shown.
